Attorney.

UNITED STATES PATENT OFFICE.

ALBERT W. BENSLEY, OF PAWTUCKET, RHODE ISLAND

ADJUSTABLE SUPPORT FOR ELECTRIC WIRES.

No. 903,807.

Specification of Letters Patent.

Patented Nov. 10, 1908.

Application filed September 15, 1908. Serial No. 453,176.

To all whom it may concern:

Be it known that I, ALBERT W. BENSLEY, a citizen of the United States, residing at the city of Pawtucket, in the county of Providence, State of Rhode Island, have invented a certain new and useful Improvement in Adjustable Supports for Electric or other Wires, of which the following is a specification.

10 My invention relates to a device for supporting electric or other wires; and the object in view is to provide a device of this character, whereby its fixed support may be mounted at different positions upon a wall 15 or other surface and at the same time permit of its insulator-posts being adjusted to a proper position to receive the wire connections.

My invention consists of a fixed member, 20 or support proper, provided with a socket at each end thereof, and which socket is surrounded by an inwardly extending flange provided with a series of grooves, and an insulator-post having an integral locking 25 portion, of the same contour as that of the socket and flange of first mentioned member.

In the accompanying sheet of drawings, Figure 1 is a front elevation of the fixed member of my device. Fig. 2 is a view, 30 partly in section and partly in elevation, showing the fixed member mounted on a wall, and also showing the insulator-post in its relative adjusted position upon said fixed member. Fig. 3 is a front elevation of my 35 improved device, showing the fixed member as in horizontal position and the insulator-posts adjusted to their proper vertical position upon said fixed member, and, Fig. 4 represents the fixed member as mounted in 40 an angular position, and the insulator-posts in their normal position upon said fixed member.

Like reference characters indicate like parts.

45 Referring to the drawings, *a* designates the fixed member, or support proper, of my device, said support having an extension or body portion *a*¹ whose ends terminate with flat circular bases *a*², *a*², each base having a 50 centrally raised circular flange *a*³ which is provided with an entering-opening *a*⁴, and said flange divides said opening from a centrally arranged recess formed in the rear of each base, as at *a*⁵, and the flange of each 55 base of said member or support has a series of V-shaped grooves *a*⁶, *a*⁶ surrounding its

entering-opening *a*⁴, in the manner shown in Figs. 1 and 2.

b designates the insulator-post of my device, said post being of L-shaped form and *c* having its lateral portion *b*¹ terminating with a centrally arranged collar *b*² having a flat circular head *b*³, and on the vertical portion of said post is mounted the usual glass insulator *c*, for securing thereto the electric 65 or other wire.

The collar *b*², of the post *b*, has a series of V-shaped shoulders *b*⁴, *b*⁴ made to fit within the grooves *a*⁶ of the flange of the member *a*, and the head *b*³, of said post *b*, is of a size to 70 fit within the recess *a*⁵ of said member.

When the device is to be mounted so that its support *a* may extend horizontally, as shown in Fig. 3, the insulator-posts *b*, *b* are positioned within their respective entering- 75 openings *a*⁴, *a*⁴ and laterally of said support, after which the device is secured to the wall *d* by screws *e*, *e* which pass through openings *f*, *f* formed in each base portion of the support *a*. 80

In cases wherein the wall surface does not permit of the support *a* being secured in a horizontal position, the posts *b*, *b* may be adjusted to a locked angular position upon said support, so that when the device is mounted 85 upon the wall it extends at an incline thereupon and with the posts in a normal vertical position, as shown in Fig. 4.

By my construction and arrangement of parts I provide a device that contains in 90 itself all that is necessary to accommodate the support being mounted in different positions upon a wall and at the same time afford the proper positioning of its insulator-posts.

Having described my invention what I 95 claim and desire to secure by Letters-Patent, is—

1. In a device of the character described, a fixed member or support having a circular base at each end thereof, and each base having a raised circular flange which divides an entering-opening from a recess formed in the rear of each base, and the flange of each base having a series of V-shaped grooves surrounding its entering-opening, an insulator-post having an integral collar and head at one end thereof, said collar having a series of V-shaped shoulders adapted to fit in the grooves of each base of first mentioned member, and said head of a size to fit the recesses of the latter. 105

2. The herein described device, compris- 110

ing a support provided with an entering-opening at each end thereof and surrounding a series of grooves, and an insulator-post having an integral collar adapted to be brought within the entering-opening and having a series of shoulders to fit in the grooves of said support, so constructed that each member may be adjusted in different angular positions relatively to each other.

10 3. In combination, the fixed support a having a circular raised flange a^2 at each end thereof, said flange dividing an entering-opening a^4 from a recess a^5 , and said flange provided with a series of V-shaped grooves 15 a^6 surrounding its entering-opening, the in-

sulator-post b having an integral collar b^2 and head b^3 at one end thereof said collar having a series of V-shaped shoulders b^4 adapted to fit within the grooves of the support, and the head of said post of a size to fit in the recessed portions of said support substantially as shown and for the purpose specified.

In testimony whereof I affix my signature in presence of two witnesses.

ALBERT W. BENSLEY.
